Attorney

UNITED STATES PATENT OFFICE.

JOSEPH A. KELLY, OF CLINTON, IOWA.

FOLDING BED.

Application filed July 11, 1922. Serial No. 574,181.

To all whom it may concern:

Be it known that I, JOSEPH A. KELLY, a citizen of the United States, residing at Clinton, in the county of Clinton and State of Iowa, have invented new and useful Improvements in Folding Beds, of which the following is a specification.

This invention relates to folding beds and particularly to a device of the character designated which is adapted to be installed as a coherent part of a building construction.

One of the objects of the invention is the construction of a built-in bed unit constituted by a cabinet having a door in the front face thereof adapted to lie substantially in the plane of a wall of the building in which said cabinet is installed, and provided with a folding bed structurally associated with said cabinet and operatively connected to the door thereof, whereby in the opening of said door the initial unfolding movement of said bed is automatically accomplished.

Another object of the invention resides in the provision of a folding bed, pivotally supported on a horizontal axis and normally forwardly inclined when folded, at an angle almost sufficient to unbalance its stability of position relative to said axis so that a slight further inclination of the bed through manually applied force will carry the center of gravity over the pivotal axis and facilitate the unfolding of said bed without the necessity of moving the dead weight thereof.

With the above and other objects in view, my invention consists in the improved folding bed illustrated in the accompanying drawings, described in the following specification, and particularly claimed, and in such variations and modifications thereof as will be obvious to those skilled in the art to which my invention relates.

In the drawings accompanying and forming a part of this specification, and wherein the preferred embodiment of my invention is illustrated:

Figure 1 is a perspective view of a portion of a building showing my improved folding bed installed as a coherent part thereof.

Figure 2 is a sectional view of a cabinet showing a side elevation of the folding bed in extended position.

Figure 3 is a transverse section taken along the line 3—3 of Figure 2.

Figure 4 is a side elevation of the bed showing the bottom section folded.

Figure 5 is a sectional view of the cabinet showing the bed completely folded.

Figure 6 is a detail view of the pivotal bracket and stop-block by which the bed is supported within the cabinet.

Referring now in detail to the several figures the numeral 1 represents a rectangular cabinet having an open front face 2 which is closed by the door 3, said door being shown in ajar position in Figure 2 and in dotted lines in Figure 5, and being shown in open position in Figure 4. To the opposite sides of said cabinet are secured brackets 4, each of said brackets being provided with an overhanging ledge 5 engaging the upper edge of a supporting board 7, shown in Figures 2 and 3, which assists the screws 8 in holding the brackets rigidly against displacement. The brackets 4 are provided with aligned apertures 9 forming bearings for a rod 10 which extends transversely the full width of the cabinet. The door 3 is rigidly secured by hinges to the lower front wall of the cabinet.

The folding bed, which is generally designated by the reference numeral 12 is also pivotally supported upon the rod 10 by means of the stop blocks 13 arranged at opposite sides thereof and provided with overhanging lugs 14 and 15 which limit the angular movement of said folding bed, the lug 14 resting upon the upper face 16 of the bracket 4 when the bed is in extended position, and the lug 15 abutting against the face 17 of said bracket when the bed is in the inclined folded position shown in Figure 5.

The folding bed is made in three sections 18, 19 and 20, said sections being hingedly secured together by being pivotally connected to opposite ends of short links 21 and 22. Each of these links is provided with a rigid transverse brace, 23 and 24 respectively, by means of which the bed is laterally stiffened. The first named section of the bed is supported upon the upper face of the stop block 13 in any suitable manner and the last section is supported upon the floor

2 by a pair of folding legs 25 which are pivotally secured to downwardly extending lugs 26 the latter being rigid with the section 20. The intermediate section 19 of the bed is 5 also supported from the floor by a pair of legs 27, similar in every respect to the legs 25 and pivotally carried by the downwardly extending lugs 28. Each of these lugs has 10 an inwardly extending flange 35 which is in the path of the hooked member 36 when the outer section of the bed is folded, as shown in Figure 4, and engaged by said hooked member to prevent said folded section from becoming unfolded when placed in the inverted position shown in Figure 5.

The provision of supporting legs adjacent the link 21 is unnecessary, the section 18 being rigidly held in a horizontal position when the bed is unfolded by the engagement of the lug 14 with the upper face 16 of the bracket 4. The upper ends of the legs of each pair project slightly above their pivotal connection with the bed frame and are pivotally connected to the ends of the 25 rods 29 and 30 respectively, the other ends of said rods being pivotally connected to the adjacent links 21 and 22. By this construction, when the folding operation of the bed has begun the angular relation assumed between each bed-section and its joining link causes the legs to be swung to a position of parallelism with the respective bed sections, and causes them to swing downwardly to a 30 position perpendicular to the floor when the bed is unfolded.

The head rail 31 is pivotally secured to rigid uprights 32 positioned at the outer ends of the bed section 20 and is foldable to the position shown in Figure 4, in which position it clampably holds the mattress, not shown, in place while the bed is being folded. The folding of the head rail is uncoordinated with the rest of the folding mechanism. In folding the bed the operator first 45 turns down the head rail 31, then raises the outer end of the section 20 and folds it upon the section 29. This act causes the legs 27 to arrange themselves parallel to the section 20, the latter assuming a position substantially at right angles to the link 22. The bed is then in the position shown in Figure 4. The operator then grasps the transverse brace rod 24 and folds the bed so that the section 19 becomes perpendicular to the link 50 21, the latter turning about its pivotal connection with the section 18 so that the folded portion of the bed lies above the latter section. The bed is then tilted downwardly into the position shown in Figure 5, the final movement of the same being performed 55 by gravity and without assistance of the operator. The bed comes to a rest in the position shown in Figure 5 with the stop block 13 in engagement with the face 17 of 60 the bracket 4.

The door 3 is operatively attached to the folding bed by means of the flexible connection 33 so that the door is independently closed after the bed has assumed its folded position of repose.

To open the bed, the handle 34 of the door is grasped and the door opened to the dotted line position shown in Figure 5. The length of the flexible connection is such that the slack in said connection is 75 taken up when the angularity of inclination of the door is the same as that of the bed. Further opening movement of the door results in the bed being pulled forward, the inclined position of the bed being such that 80 the stability of its equilibrium is readily upset and it falls forward by gravity to a horizontal position. The bed is then unfolded by reversing the sequence of operations by which it was folded.

A folding bed unit of the character herein described is particularly adapted to be built into the walls of the rooms of houses and especially of rooms which are used in the day time for other purposes than that 90 of sleeping apartments. The cabinet 1 is designed to be built in with the front face thereof flush with the surface of the wall, and the door lends itself to any form of decoration or ornamentation which will 95 harmonize or merge with the wall decoration so as to become a part thereof. In the illustration in Figure 1 the door is panelled as shown at 37 to match the panelling of the surrounding wall.

But it is not intended that the possibilities of use of my improved folding bed unit shall be restricted to built-in constructions for the cabinet may constitute a piece of furniture affording a compact and artistic 105 construction adaptable for use in many places where, on account of lack of room, there would be no place for a full length bed.

Having described my invention what I 110 claim as new and desire to secure by Letters Patent, is:—

1. A folding bed unit comprising a bed and a support therefor, cooperating hinge elements carried by said support and bed for pivotally mounting the latter, said hinge elements being formed with means for normally maintaining said bed in stable equilibrium about its pivotal axis but close to a position of instability.

2. A folding bed unit comprising a cabinet having an open front, a folding bed pivotally mounted within said cabinet and swingable relative thereto about a pivotal axis when said bed is folded, cooperating means carried by said bed and cabinet for normally maintaining said bed in stable equilibrium about said axis but close to a position of instability, a door for closing the open front of said cabinet and tractive 130

means operatively connecting said door and the upper part of the folded bed, said means being of such length as to permit the bed to be tipped to a position of unstabled equilibrium by the opening movement of said door.

3. A folding bed unit comprising a cabinet, a bracket in said cabinet, a folding bed pivotally mounted with respect to said bracket and having a stop block secured thereto and engageable with said bracket, said stop block and bracket having cooperat-

ing faces to limit the movement of said bed to a horizontal position in one direction and to an inclined position in stable equilibrium at the other limit of its range of movement.

In testimony whereof I have hereunto set my hand in presence of two subscribing witnesses.

JOSEPH A. KELLY.
